[57] CLAIM

The ornamental design for a combination work bench
and bed, as shown and described.

DESCRIPTION

FIG. 1 is a perspective view of the combination work
bench and bed shown in the bed configuration.

FIG. 2 is a front elevational view of the combination
work bench and bed shown in the bed configuration.

FIG. 3 is a perspective view of the combination work
bench and bed shown in the work bench configuration.

FIG. 4 is a side elevational view of the combination
work bench and bed shown in the work bench configura-
tion; the end not shown in this figure is a mirror image
of the end which is shown.

FIG. 1

FIG. 2

FIG. 3

FIG. 4
